TAPE RECORDER

Sheldon Lee Pastor, Chicago, and Robert L. Deschamps,
West Chicago, Ill., assignors to Revere Camera Com-
pany, Chicago, Ill., a corporation of Delaware

Filed July 16, 1962, Ser. No. 70,937

Term of patent 14 years

(Cl. D26—14)

Fig. 1

Fig. 2.

Fig. 3.

*Fig. 4.**Fig. 5.*FIG. 1 is a perspective view of a tape recorder showing our new design;

FIG. 2 is a top plan view, to an enlarged scale;

FIG. 3 is a front elevational view, to an enlarged scale;

FIG. 4 is a side elevational view, to an enlarged scale, the opposite side being substantially a mirror image thereof; and

FIG. 5 is a rear elevational view thereof, to an enlarged scale.

The bottom is free of ornamentation.

The tape deck not shown is conventional.

We claim:

The ornamental design for a tape recorder, as shown and described.
